UNITED STATES PATENT OFFICE

97,009

DESIGN FOR AN AUTOMOBILE SIGNAL LAMP CASING

Louis G. Kailer and Jefferson C. Gibson,
Chicago, Ill.

Application December 6, 1934, Serial No. 54,318

Term of patent 3½ years

To all whom it may concern:

Be it known that we, Louis G. Kailer and Jefferson C. Gibson, citizens of the United States, residing at Chicago, in the county of Cook and State of Illinois, have invented a new, original, and ornamental Design for an Automobile Signal Lamp Casing, of which the following is a specification, reference being had to the accompanying drawing, forming part thereof.

Figure 1 is a perspective view; Fig. 2 is a bottom view; and Figure 3 is a face view in elevation of an automobile signal lamp casing showing our new design.

We claim:

The ornamental design for an automobile signal lamp casing, as shown.

LOUIS G. KAILER.
JEFFERSON C. GIBSON.
